UNITED STATES PATENT OFFICE.

HARRY L. SWAN, OF MILBANK, SOUTH DAKOTA.

CIGARETTE-MAKING DEVICE.

Substitute for application Serial No. 180,229 filed April 1, 1927. This application filed December 6, 1928.
Serial No. 324,262.

This invention relates to cigarette forming devices and has special reference to a device of this character adapted for use in the home or office and providing means to 5 form and make cigarettes, either oval or round and of any length up to four inches.

The present application is a substitute for an abandoned application Serial No. 180,229 filed April 1, 1927.

One object of the invention is to provide 10 a simple and efficient device by means of which any person, without particular skill, can make a number of cigarettes at a time, as for instance sufficient to fill a cigarette case or more.

A second object of the invention is to provide 15 an improved device of this character which can be used for making either oval or round cigarettes, in accordance with the construction of the device, and of any desired length as for instance up to four inches long.

A third object of the invention is to provide 20 an improved device of this character by means of which a cigarette may be formed which can be carried in a case and will not disrupt and spill the contents under ordinary circumstances, this being accomplished by provision of means whereby the end of the 25 cigarette paper may be twisted during the formation.

A fourth object of the invention is to provide 30 an improved device of this character having a filling tube and a plunger working therein which plunger is provided intermediate its ends with a shoulder preventing the plunger from being pushed too far through the tube, this plunger forming a simple means to remove the tobacco from the 35 forming tube when the latter is filled and push it into the cigarette paper which has been previously wrapped and cemented or glued to form around said forming tube.

A fifth object of the invention is to provide 40 an improved device of this character having a hopper or reservoir provided with an inverted frusto-conical cover open at the middle so that the filling of the hopper may be greatly facilitated, the cover owing to its 45 form preventing tobacco from spilling when using or when the device is laid down in a horizontal position.

With the above and other objects in view as will be hereinafter apparent, the invention 50 consists in general of certain novel de-

tails of construction and combinations of parts hereinafter fully described, illustrated in the accompanying drawings and specifically claimed.

In the accompanying drawings like characters of reference indicate like parts in the several views, and:

Figure 1 is a vertical median section 60 through the device with the cover raised.

Figure 2 is a side elevation of the piston or plunger.

Figure 3 is a plan view of the cover.

Figure 4 is a side elevation of the assembled device with a cigarette paper wrapped 70 thereon and ready to be cemented or glued.

In the construction of the invention there is provided a cylindrical hopper or reservoir *e* having an inverted frusto-conical bottom open at the center and from this bottom 75 extends a forming tube *g* of circular cross-section but which may be of oval cross-section as shown at *h*. Movable in this hopper and tube is a plunger *b* having at its lower end a piston head *f* of circular form but 80 which may be modified for use with the oval tube *h* as shown at *i*. At the top of the plunger rod *b* is provided a head *a* and intermediate the ends of said rod is a collar *d* which is of sufficient size to engage the 85 mouth opening at the upper end of the tube and thus limit the downward movement of the plunger rod. On the hopper *e* is tightly fitted a closure *c* of inverted frusto-conical form and open at the middle so that tobacco 90 may be readily poured into the hopper through this closure or cover, the form of the cover directing the tobacco downwardly into the hopper and preventing spilling of the same. Furthermore, due to this form 95 tendency of the tobacco to spill out of the hopper when the device is laid on its side is prevented.

In use the cover is placed on the hopper and the plunger inserted with the head *f* 100 in the forming tube so that tobacco may be poured through the cover into the hopper and not escape through this tube. Then a cigarette paper *k* having a gummed edge *j* is wrapped around the forming tube as 105 shown in Figure 2 and the gummed edge moistened and stuck down. The cigarette paper is then drawn off the end of the forming tube and twisted to cross the lower end of the cigarette tube. Next the plunger is 110 raised to allow a charge of tobacco to pass

into the tube, *g* and is then pushed down to compact this charge, the user holding his finger over the twisted end of the cigarette tube and pressing it against the forming tube 5 during the compacting. Then the user removes his finger and the plunger is pushed further down which forces the compacted charge out of the forming tube and at the same time strips the cigarette tube off of this 10 forming tube. Finally, the upper open end of the cigarette may, if desired, be twisted although with the tobacco properly compacted this is not always necessary.

There has thus been provided a simple 15 and efficient device of the kind described and for the purpose specified.

It is obvious that minor changes may be made in the form and construction of the invention without departing from the material spirit thereof. It is not, therefore, desired to confine the invention to the exact 20 form herein shown and described, but it is desired to include all such as properly come within the scope claimed.

25 Having thus described the invention, what is claimed as new, is:

1. In a hand cigarette forming device, the

combination of a hopper having an inverted frusto-conical bottom open at the center and a forming tube extending downwardly therefrom, an inverted frusto-conical cover seated on the upper end of said hopper and open at the center, and a plunger passing through said cover and having a lower end reciprocable in the tube and provided with 30 a piston head.

2. In a hand cigarette forming device, the combination of a hopper having an inverted frusto-conical bottom open at the center and a forming tube extending downwardly therefrom, an inverted frusto-conical cover seated on the upper end of said hopper and open at the center, a plunger passing through said cover and having a lower end and reciprocable in the tube and provided with a piston head, and a collar on said plunger of greater diameter than the opening in the tube and spaced above the piston head, said collar forming means to limit downward movement 40 of the head in said tube and also forming 45 a closure valve for the upper end of the tube.

In testimony whereof I affix my signature.

HARRY L. SWAN.
